COLLECTING MECHANISM FOR ROD-SHAPED ARTICLES

Desmond Walter Molins, Félix Frédéric Ruau, and Samuel Robert Chown, Deptford, London, England, assignors to Molins Machine Company Limited, Deptford, London, England

Application May 13, 1941, Serial No. 393,298
In Great Britain May 18, 1940

10 Claims. (Cl. 226—2)

This invention concerns improvements in or relating to collecting mechanism.

It is to be understood that when a receptacle is stated to be "filled" it is not necessarily completely full.

According to the present invention there is provided collecting mechanism of the kind referred to, wherein an article-distributor is supported above the path of the receptacle which is being filled and is arranged to move into the receptacle with a component of movement in the direction of movement of the latter so as to move articles in the receptacle away from the inclined guide and towards the leading wall of the receptacle. A leveller-device (e. g. a fixed guide or guides) may be disposed above the path of a receptacle which is being filled and arranged to extend in the direction of movement of the receptacle, said levelling-device co-operating with the article-distributor to determine the height of the articles in a receptacle as the latter becomes filled with articles.

A downwardly depending-element may be mounted for movement towards the article-distributor by articles being delivered to the receptacle, the depending-element and the article-distributor being so constructed that the article-engaging surfaces thereof intersect for the purpose of aligning articles so that the longitudinal axes of the articles are substantially parallel with the bottom of the receptacle to which they are being delivered.

The rear surface of the article-distributor may be provided with a rib or ribs which is or are parallel with the bottom of a receptacle which is being filled and normal to the direction of movement of the receptacle during the filling operation. The article-engaging surface of the depending-element may be provided with a rib or ribs which is or are parallel with the bottom of a receptacle which has been filled and normal to the direction of movement of the receptacle during the filling operation. The article-engaging surface of the inclined guide may be provided with a rib or ribs which is or are parallel with the bottom of a receptacle which is being filled and normal to the direction of movement of the receptacle during the filling operation. The article-engaging surface of the inclined guide may be provided with a rib or ribs which is or are parallel with the bottom of a receptacle which is being filled and normal to the direction of movement of the receptacle during the filling operation.

Some embodiments of the invention will be

described by way of example with reference to the accompanying drawings in which:

Figure 1 is a vertical sectional view showing a form of receptacle in which cigarettes are collected.

Figure 2 is a plan of mechanism for collecting cigarettes.

Figure 3 is a side elevation of Figure 2 looking in the direction of the arrow 4, parts of the apparatus being broken away in order to show other parts more clearly.

Figure 4 is an end elevation to an enlarged scale looking in the direction of the arrow 5, Figure 2, the upper mechanism being omitted from the figure.

Referring to the drawings, cigarettes which are severed from a continuous cigarette rod formed on a cigarette-making machine (not shown) of the continuous rod type, are moved transversely out of the rod line and are deposited upon a catcher band 4. The catcher band moves the cigarettes transversely of their longitudinal axes and cigarettes roll off the catcher band at the delivery end thereof. At the delivery end, the catcher band passes around a roller 5 which is supported for rotation in frames 6 supported on a base 48. For simplicity the frames 6 are shown broken away. Cigarettes falling from the catcher band engage a downwardly depending pivoted flap 7 which, when engaged by the cigarettes, moves about its pivot 8 away from the catcher band. A counterweight 9 is provided to balance the flap 7.

35 Around a rotatable support 10 having a fixed axis of rotation, there is arranged a plurality of paddles 11 which comprise cigarette-distributors. The axis of rotation of the support 10 is at a slightly lower level than the axis of rotation of the roller 5. The paddles are parallel to and offset from the axis of rotation of the support 10 and are inclined rearwardly considered in the direction of rotation of the support so that they are tangential to and equispaced around a circle 45 concentric with the axis of rotation. The free ends of the paddles 11 are moved through a path such that at the point where the free end of a paddle is closest the band 4, the distance between the latter and such free end of a paddle is slightly less than the combined diameters of two cigarettes. The pivoted flap 7 is slotted as indicated by the reference numeral 12, see Figure 3, so as to permit the cigarette-engaging surfaces of the paddles 11 and the flap 7 respectively to intersect one another when the flap 7 is moved towards

the paddles by cigarettes being delivered from the delivery end of the band 4.

Receptacles R into which the cigarettes are to be delivered are supported for movement in a closed path, the receptacles being supported by conveyor-mechanism which moves the receptacles beneath the band 4 as can be seen from Figure 3. The conveyor-mechanism comprises two chains 14 and 15 which are arranged one above the other, the chains passing around sprocket wheels 16 and 17. The sprocket wheels 17 are connected to each other by a hub 18 which is mounted for rotation about the spindle 19. The spindle 19 is supported in a bearing 20. The sprocket wheels 16 are connected by a hub 21 which is mounted for rotation about a spindle 22, the spindle 22 being supported in a bearing 23.

Rotation of the sprocket wheels 16 and 17 is effected by a ratchet wheel 24 which is connected with the lower sprocket wheel 16. The ratchet wheel 24 is rotated by two ratchet pawls 25 and 26 which are eccentrically mounted on a spindle 27 the latter being driven by an electrical motor, not shown. The electrical motor drives only the collecting mechanism. The pawls 25 and 26 are urged inwardly towards the teeth of the ratchet wheel by springs 28 and 29. The ratchet wheel drive is of conventional form and not new.

The rotatable support 10 is also driven from the spindle 27, the drive for the support being effected through a worm 30 mounted on the spindle 27, the drive for the support being effected through a worm 30 mounted on the spindle 27, a wormwheel 31 mounted on a stud 32, a V pulley 33 is also mounted on the stud 32, a further V pulley 34 (see Figure 3) mounted on the spindle 35 of the rotatable support 10 and a belt 36 which connects the pulleys 33 and 34.

The receptacles R are arranged to be carried in supports driven by the chains 14 and 15. These supports comprise U shaped straps 37 which support and are secured to cross-bars 38 and 39. J shaped members 40 and 41 into which the receptacles fit with a push fit are themselves secured to the cross-bars 38 and 39. To each of the receptacles there is secured a pair of stops 42 and 43 and the receptacles are movable relatively to the conveyor in the direction of movement thereof to the extent permitted by the stops 42 and 43.

At the bottom of the receptacle there is provided a flexible strip S. The strip lies along the bottom of the receptacle and the opposite ends of the strip extend downwardly as shown in the drawings. In order that the strips do not foul the abutting receptacles, the latter are cut away as indicated by the reference numeral 101. If desired, a plurality of flexible strips may be contained in a receptacle, the strips being superimposed one upon the other as indicated in Figure 1. The strips are preferably of paper or textile material and when the cigarettes are delivered into the receptacle they are delivered on to the uppermost strip at the bottom of the receptacle. The purpose of making the receptacle movable relatively to the conveyor-mechanism is to permit the opposite ends of the uppermost strip to be gripped and drawn about the cigarettes in the receptacle to enable the cigarettes to be removed from the receptacle after the latter has been filled, without the necessity of effecting the complete removal of a receptacle from the conveyor-mechanism. By providing a plurality of strips the operator is relieved of having to place a strip in position whenever a receptacle is emptied. When,

however, strips S are not employed, the receptacles can, if desired, be lifted bodily out of the J shaped members and either emptied and replaced or the removed, filled receptacles can be replaced by other empty receptacles.

While the receptacles are moving along the straight portions of the run of the conveyor, the receptacles, which are similar to that shown in Figure 1 and which have straight, vertical end walls, are as can be seen from Figures 3 and 4, in endwise abutting relationship with each other and the rear stops 43 engage the J shaped members 40 (see Figure 4). The chains 14 and 15 are guided during the straight portion of their run by guides 44 and 45.

In order to support the weight of the receptacles during and after filling thereof, the cross-bars 39 support vertical bars 46 at the lower end of each of which there is mounted a roller 47. The rollers 47 engage the base 48 on which the collecting apparatus is mounted. To the bottom of each receptacle there is secured a roller 49 which engages with a track 50 while the receptacle is being moved around the sprockets 16 and 17, the track serving to guide the receptacles around this portion of the path. The ends of the strips slide over the base 48 and movement of the receptacles causes them to trail on the base 48. The space between the roller 49 and the base 30 48 prevents the strips fouling the roller 49.

As can be seen from Figures 3 and 5, the opposite ends of the receptacles R are provided with slots 100, these slots permitting the passage of the receptacles past a downwardly inclined guide 35 52 which is secured to a bracket 53 supported by the frames 6 and directs cigarettes into the receptacle which is being filled. The slotted ends of the receptacles therefore comprise spaced elements which extend upwardly and outwardly.

40 The word "outwardly" when used in connection with the spaced elements in the claims, means in an endwise direction from the base of the receptacle which supports the strips. In the construction shown in Figure 1, the spaced elements 45 commence some distance inwardly from the end wall, since the bottom of the receptacle is also slotted near the end walls. It will be seen, therefore, that in the construction shown in Figure 1, the spaced elements extend upwardly and outwardly, the lower end portions being directed outwardly. The lower end portion could, if necessary, be horizontal and there might even be a radius between the horizontal and vertical portions. In all such cases, these spaced elements 55 can be said to extend upwardly and outwardly as shown.

The inclined guide extends downwardly almost to the bottom of a receptacle. The paddles 11 are provided with ribs 54 and the flap 7 and inclined guide 52 are respectively provided with 60 similar ribs 55 and 56. The ribs are so arranged that they are parallel to the bottom of the receptacle which is being filled and they are normal to the direction of movement of that receptacle.

65 A detector-device is provided to stop the electrical motor driving the collecting-mechanism should the supply of cigarettes on the band 4 cease. This detector-device comprises a flap 57 which is pivoted at 58 and counterbalanced by a weight 59, the flap being moved upwardly away from the band 4 by the passage of cigarettes being delivered to a receptacle and which accumulate under the flap 57 due to the shape of its free end (as shown in Figure 4) before it can 70 lift. Should there, as shown in Figure 4, be no

cigarettes on the band, the flap 57 engages the band 4. To the spindle 58 there is connected a mercury switch 60 and this switch controls the electrical motor.

A pair of guides 61 having upturned ends 62 comprise a leveller-device which is disposed above the receptacle being filled. The guides extend in the direction of movement of the receptacle and are so arranged as to co-operate with the paddles 11 to determine the height of the cigarettes in the receptacle as the latter becomes filled.

Side guides 63 are provided to prevent undue endwise movement of the cigarettes during their movement from the band 4 into a receptacle, and fit over strip 630 on the receptacles to keep the latter accurately aligned.

The operation of the apparatus is as follows. The receptacles to be filled are positioned in endwise abutting relationship as shown in Figures 3 and 4 by sliding them till the stops 43 engage the strops 37 and the lower end of the inclined guide 52 is located near to the bottom front corner of the leading receptacle. The front wall of the receptacle and the guide 52 form a substantially V shaped space for the reception of cigarettes from the band 4. It is preferable, particularly when filling deep receptacles to arrange for this V shaped space to be manually filled before the automatic filling commences. It is, however, to be understood that this is only necessary when the operation of the apparatus is first commenced, because once the first receptacle has been filled, provided that the succeeding receptacles all approach the filling position in endwise abutting relationship, the filling of the successive receptacles will be continuous while the supply of cigarettes is maintained. The lengthwise movement of the receptacles by the conveyor is correlated with the rate at which cigarettes are normally delivered by the band 4 so that the volume of cigarettes arriving equals in space the volume of receptacle space passing the guide 52.

Starting from the point at which the V shaped space is manually filled, the chains 14 and 15 move the receptacles slowly and intermittently forward and cigarettes fall from the delivery end of the band 4 towards the receptacle being filled. Some of the cigarettes fall directly between the free ends of the paddles 11 and the band 4 towards the inclined guide 52. These cigarettes are straightened up relatively to the receptacle by engagement with the bars 55 and 56. Some of the cigarettes coming as they do in a mass move against the pivoted flap 7 and urge the latter towards the paddles 11 so that the cigarette engaging surfaces of the pivoted flap and the paddles intersect each other. The intersecting surfaces tend to straighten up, relatively to the receptacle, those cigarettes which do not fall directly towards the receptacle and the ribs 54 on the paddles 11 further assist in the straightening operation. Thus there is a mass of cigarettes held in the space above the intersecting paddles and flap on the one side and the band 4 on the other. Since the ends of the paddles 11 is more than the diameter of one cigarette from the band 4, the paddles as they move down will not damage or crush the cigarettes.

As the receptacle moves forwardly the cigarettes have a tendency, particularly when the receptacles are relatively deep receptacles, to move downwardly away from the leading end of the receptacle so that a dip is formed in the upper level of the cigarettes in the receptacle. The paddles

11 operate to tend to maintain the level of the cigarettes in the receptacle, pressing downwardly on the cigarettes in the vicinity of the upper end of the inclined guide 52 and moving them away from the guide and bodily towards the leading end of the receptacle. The guides 61 co-operate with the paddles in this levelling operation by limiting the extent of upward movement of the cigarettes so moved by the paddles. In Figures 10 3 and 4, the guides 61 are shown as fixed guides. By so mounting the guides 61, the tendency for cigarettes to be jammed between the paddles and the guides is reduced.

As the rear wall of a receptacle which is being filled approaches the inclined guide 52, the latter passes through the slot 100 formed in the rear wall of the receptacle and into the slot formed in the front wall of the next succeeding receptacle. Thus, as the receptacle moves away from the filling position, the second receptacle receives cigarettes. There is, of course, a period when the first and second receptacles are simultaneously receiving cigarettes. During the transition from the first to the second receptacle, the paddles tend to prevent the accumulation of cigarettes on the upper edges of the receptacles. If desired, however, the chains 14 and 15 may be driven by a variable speed mechanism which automatically increases the speed at which the receptacles are moved during the change of feeding from the first to the second receptacle. For example as described below, the electrical motor driving the conveyor may be controlled by a rheostat which is in turn controlled by a feeler arranged to engage an element carried by the tray to alter the rheostat when a tray edge is passing a predetermined position.

Current from one terminal of the mains 200 goes through the mercury switch 60 and then to a motor 201 and to a resistance 202 and a switch arm 203 back to the mains. Normally (i. e. during filling of the middle portion of a tray) the switch arm 203 is at the left or chain line position. When the receptacles reach a position when the feeding changes from one conveyor to another, a plate or cam 204 fixed to the outer side of each receptacle strikes a spring controlled lever 205 fixed to the switch arm 203. The resistance 202 is arranged as a rheostat over which a contact on the switch arm 203 moves to reduce the resistance as the switch arm moves in an anti-clockwise direction.

The length of the plate will be such as to limit the period during which the motor is speeded up to that desired in any particular case. Thus, as the switch arm is moved from left to right along the resistance, so the speed of the motor 201 is increased. As can be seen from the drawings, the motor 201 drives the spindle 27 by a belt 206 which passes over pulleys 207, 208.

In the position of the receptacles shown in Figure 4, the cam 204 is shown rather too far forward on the receptacles, but it has been shown in this position in order to illustrate the action of the cam on the lever arm 205. Obviously in practice, this cam would be placed at a position where it would be effective at the desired time for the purpose in view. A stop 209 is provided to limit the extent of movement of the switch arm 203 and lever arm 205 under the influence of a coil tension spring 210.

If it is desired to increase the speed of the motor more rapidly than by the apparatus shown, this can be achieved by reducing the length of the lever 205. Preferably the speed to which the

motor is increased is twice that of the speed at which it is operated when driving the mechanism for normal running.

When a receptacle has been filled, it is moved to the opposite side of the run of the chains 14, 15, that is the side shown in the lower part of Figure 3. The receptacle can then be shifted manually so as to cause it to move rearwardly away from the other receptacle supported on that side of the run. The opposite ends of the uppermost strip S can then be lifted upwardly by the machine operator through the slots 100 and towards each other about the cigarettes in the receptacle and the cigarettes may then be lifted out of the receptacle by the strip. The rearward movement of the receptacle is limited by the stop 42 engaging the J shaped member 41. After the articles have been removed from the receptacle, the latter can again be moved manually into abutting relationship with the preceding receptacle.

In all cases where flexible strips are arranged at the bottom of a receptacle and where the ends of the strips hang downwardly, the receptacles must be so arranged that sufficient space is left between the bottom of succeeding receptacles to provide room for the strips and yet ensure that the top portions of succeeding receptacles abut so as to prevent cigarettes falling between the two receptacles.

It will, however, be appreciated that the use of flexible strips in conjunction with receptacles is not limited to constructions in which receptacles are moved in continuous, closed paths.

What we claim as our invention and desire to secure by Letters Patent is:

1. Collecting-mechanism comprising in combination, means to move articles transversely to their longitudinal axes to a delivery position, means to move a receptacle lengthwise below said position so that articles are delivered first into one end of the receptacle and thereafter to successive positions along the length of the receptacle, a downwardly inclined guide to direct articles into a receptacle, and an article-distributor supported above the path of a receptacle, means supporting said article-distributor for movement forwardly into the receptacle with a component of movement in the direction of movement of the latter so as to move articles in the receptacle away from the inclined guide and towards the leading wall of the receptacle.

2. Collecting-mechanism comprising in combination, means to move articles transversely to their longitudinal axes to a delivery position, means to move a receptacle lengthwise below said position so that articles are delivered first into one end of a receptacle and thereafter to successive positions along the length of the receptacle, a downwardly inclined guide to direct articles into a receptacle, an article-distributor supported above the path of a receptacle, means supporting said article-distributor for movement forwardly into the receptacle with a component of movement in the direction of movement of the latter so as to move articles in the receptacle away from the inclined guide and towards the leading wall of the receptacle, and a leveller-device extending lengthwise in the direction of movement of the receptacle which is being filled, said levelling-device co-operating with the article-distributor to determine the height of the articles in a receptacle.

3. Collecting-mechanism comprising in combination, means to move articles transversely to their longitudinal axes to a delivery position,

means to move a receptacle lengthwise below said position so that articles are delivered first into one end of a receptacle and thereafter to successive positions along the length of the receptacle, a downwardly inclined guide to direct articles into a receptacle, an article-distributor supported above the path of a receptacle and arranged to move with a component of movement in the direction of movement of the latter so as to move articles in a receptacle away from the inclined guide and towards the leading wall of the receptacle, and a downwardly depending element mounted for movement towards the article-distributor by articles being delivered to a receptacle, the said depending-element and the article-distributor being so constructed that the article engaging surfaces thereof intersect for the purpose of aligning articles with their longitudinal axes substantially parallel with the bottom of the receptacle to which they are being delivered.

4. Collecting mechanism comprising in combination, means to move articles transversely to their longitudinal axes to a delivery position, means to move a receptacle lengthwise below said position so that articles are delivered first into one end of a receptacle and thereafter to successive positions along the length of the receptacle, a downwardly inclined guide to direct articles into a receptacle, an article-distributor supported above the path of a receptacle and arranged to move with a component of movement in the direction of movement of the latter so as to move articles in a receptacle away from the inclined guide and towards the leading wall of the receptacle, a downwardly depending element mounted for movement towards the article-distributor by articles being delivered to a receptacle, the said depending-element and the article-distributor being so constructed that the article-engaging surfaces thereof intersect for the purpose of aligning articles with their longitudinal axes substantially parallel with the bottom of the receptacle to which they are being delivered, and a leveller-device extending lengthwise in the direction of movement of a receptacle which is being filled, said levelling-device co-operating with the article-distributor to determine the height of the articles in a receptacle.

5. Collecting mechanism comprising in combination, means to move articles transversely to their longitudinal axes to a delivery position, means to move a receptacle lengthwise below said position so that articles are delivered first into one end of a receptacle and thereafter to successive positions along the length of the receptacle, a downwardly inclined guide to direct articles into a receptacle, a rotatable support, and a plurality of paddles mounted on the support for movement therewith, said paddles being supported for movement in the receptacle with a component of movement in the direction of movement of the receptacle which is being filled so as to move articles in the receptacle away from said inclined guide and towards the leading wall of the receptacle.

6. Collecting mechanism comprising in combination, means to move articles transversely to their longitudinal axes to a delivery position, means to move a receptacle lengthwise below said position so that articles are delivered first into one end of a receptacle and thereafter to successive positions along the length of the receptacle, a downwardly inclined guide to direct articles into

a receptacle, a rotatable support, a plurality of paddles mounted on the support for movement therewith, said paddles being supported for movement in the receptacle with a component of movement in the direction of movement of a receptacle which is being filled so as to move articles in a receptacle away from said inclined guide and towards the leading wall of the receptacle, and a leveller-device extending lengthwise in the direction of movement of a receptacle which is being filled, said levelling-device co-operating with the article-distributor to determine the height of the articles in a receptacle.

7. Collecting mechanism comprising in combination, means to move articles transversely to their longitudinal axes to a delivery position, means to move a receptacle lengthwise below said position so that articles are delivered first into one end of a receptacle and thereafter to successive positions along the length of the receptacle, a downwardly inclined guide to direct articles into a receptacle, a rotatable support, a plurality of paddles mounted on the support for movement therewith, said paddles having a component of movement in the direction of movement of a receptacle which is being filled so as to move articles in a receptacle away from said inclined guide and towards the leading wall of the receptacle, a downwardly depending element mounted for movement towards the article-distributor by articles being delivered to a receptacle, the said depending element and the article-distributor being so constructed that the article-engaging surfaces thereof intersect for the purpose of aligning articles with their longitudinal axes substantially parallel with the bottom of the receptacle to which they are being delivered, and a leveller-device extending lengthwise in the direction of movement of a receptacle which is being filled, said levelling-device co-operating with the article-distributor to determine the height of the articles in a receptacle.

8. Collecting mechanism comprising in combination, means to move articles transversely to their longitudinal axes to a delivery position, means to move a receptacle lengthwise below said position so that articles are delivered first into one end of a receptacle and thereafter to successive positions along the length of the receptacle, a downwardly inclined guide to direct articles into a receptacle, an article-distributor supported above the path of a receptacle, means supporting said article-distributor for movement forwardly into the receptacle with a component of movement in the direction of movement of the latter so as to move articles in a receptacle away from the inclined guide and towards the leading wall of the receptacle, and at least one rib located on the article engaging surface of the inclined guide, said rib being parallel with the bottom of a receptacle which is being filled and normal to the direction of movement of a receptacle while the latter is being filled.

9. Collecting mechanism comprising in combination means to move articles transversely to their longitudinal axes to a delivery position, 65

means to move a receptacle lengthwise below said position so that articles are delivered first into one end of a receptacle and thereafter to successive positions along the length of the receptacle, 5 a downwardly inclined guide to direct articles into a receptacle, an article-distributor supported above the path of a receptacle and arranged to move with a component of movement in the direction of movement of the latter so as to move articles in a receptacle away from the inclined guide and towards the leading wall of the receptacle, a downwardly depending element mounted for movement towards the article-distributor by articles being delivered to a receptacle, 10 the said depending-element and the article-distributor being so constructed that the article-engaging surfaces thereof intersect for the purpose of aligning articles with their longitudinal axes substantially parallel with the bottom of the receptacle to which they are being delivered, at least one rib located on the article engaging surface of the inclined guide, and at least one rib located on the article-engaging surface of the depending-element, said ribs each being parallel 15 with the bottom of a receptacle which is being filled and normal to the direction of movement of the receptacle while the latter is being filled.

10. Collecting mechanism comprising in combination, means to move articles transversely to their longitudinal axes to a delivery position, 30 means to move a receptacle lengthwise below said position so that articles are delivered first into one end of a receptacle and thereafter to successive positions along the length of the receptacle, a downwardly inclined guide to direct articles into a receptacle, a rotatable support, a plurality of paddles mounted on the support for movement therewith, said paddles having a component of movement in the direction of movement of a receptacle which is being filled so as to move articles in a receptacle away from said inclined guide and towards the leading wall of the receptacle, a downwardly depending element mounted for movement towards the article-distributor 35 by articles being delivered to a receptacle, the said depending element and the article-distributor being so constructed that the article engaging surfaces thereof intersect for the purpose of aligning articles with their longitudinal axes substantially parallel with the bottom of the receptacle to which they are being delivered, a leveller-device extending lengthwise in the direction of movement of a receptacle which is being filled, said levelling-device co-operating with the article-distributor to determine the height of the articles in a receptacle, at least one rib on the rear surface of a paddle, at least one rib on the article engaging surface of said inclined guide, and at least one rib on the article engaging surface of the depending-element, said ribs each being parallel 40 with the bottom of a receptacle which is being filled and normal to the direction of movement of the receptacle while the latter is being filled.
